[57] **CLAIM**

The ornamental design for a lint remover, as shown.

DESCRIPTION

FIG. 1 is a top, front and right side perspective view of a lint remover showing my new design;

FIG. 2 is a top plan view thereof;

FIG. 3 is a front elevational view thereof;

FIG. 4 is a left side elevational view thereof;

FIG. 5 is a rear elevational view thereof;

FIG. 6 is a bottom plan view thereof;

FIG. 7 is a top plan view with a head guard mounted thereto;

FIG. 8 is a front elevational view thereof;

FIG. 9 is a left side elevational view thereof; and

FIG. 10 is a bottom plan view thereof.

The lint remover is shown with the head guard removed in FIGS. 1-6 for clarity of illustration.
